DESIGN FOR AN EARRING

Leo Brandfeld, New York, N. Y.

Application May 10, 1943, Serial No. 110,166

Term of patent 14 years

To all whom it may concern:

Be it known that I, Leo Brandfeld, a citizen of Czechoslovakia, residing at New York, in the county of New York and State of New York, have invented a new, original, and ornamental Design for an Earring, of which the following is a specification, reference being had to the accompanying drawing, forming part thereof.

Fig. 1 is a front view of an earring, showing my new design;

Fig. 2 is a side elevation thereof, partially in section; and

Fig. 3 is a rear view thereof.

I claim:

The ornamental design for an earring, as shown.

LEO BRANDFELD.
